Primary Examiner—Lucy Lieberman

[57] CLAIM

The ornamental design for a combine bottle and cap, as shown and described.

DESCRIPTION

FIG. 1 is a perspective view of a combined bottle and cap showing our new design;
FIG. 2 is a top plan view thereof;
FIG. 3 is a bottom plan view thereof;
FIG. 4 is a front elevational view thereof, the rear view being a mirror image; and,
FIG. 5 is a right side elevation, the left side elevation being the same.
